TOOTHBRUSH

Hans Halm, Herne, Westphalia, Germany, assignor to
Dr. Best G.m.b.H., Cologne, Turmhaus am Neumarkt,
Germany, a company of Germany

Filed Apr. 10, 1967, Ser. No. 6,605

Term of patent 7 years

(Cl. D9—2)

FIG. 1 is a side elevation view of a toothbrush, showing my new design;

FIG. 2 is a front elevation view;

FIG. 3 is a rear elevation view;

FIG. 4 is an end elevation view taken from the bristle carrying end thereof; and

FIG. 5 is an end elevation view taken from the opposite end thereof.

The dominant features of my design reside in the portions shown in full lines.

It is to be understood that the bristles shown fragmentarily in FIG. 1 and partially in FIGS. 1, 2, 4 and 5 are intended to cover the entire area encompassed thereby.

The drawing is shaded to show contrast.

I claim:

The ornamental design for a toothbrush, as shown and described.
